UNITED STATES PATENT OFFICE.

MARION HURLBURT, OF NEW YORK, N. Y.

ARBOR FOR MULTIGRAPH MACHINES.

1,410,014.

Specification of Letters Patent. Patented Mar. 21, 1922.

Application filed May 16, 1921. Serial No. 470,077.

To all whom it may concern:

Be it known that I, MARION HURLBURT, citizen of the United States, residing at New York, in the county of New York and State 5 of New York, have invented certain new and useful Improvements in Arbors for Multigraph Machines, of which the following is a specification.

This invention relates generally to multigraphing machines, having more particular reference to a roll or arbor for mounting the ribbons to which the inking sheets are attached.

The invention has for an object to provide 15 a simple form of arbor which will facilitate the insertion and removal of the ribbon.

For further comprehension of the invention, and of the objects and advantages thereof, reference will be had to the following description and accompanying drawings, and to the appended claim in which the various novel features of the invention are more particularly set forth.

Fig. 1 of the drawings is a perspective 25 view of a roll or arbor for multigraphing machines constructed according to my invention, showing the two separable elements thereof drawn apart.

Fig. 2 is a longitudinal sectional view 30 taken on the line 2—2 of Fig. 1.

The arbors or rolls heretofore employed in carrying the ribbons in multigraphing machines have been disadvantageous in that an undesirable length of time was necessitated 35 for their removal. My improved arbor while following the general outlines of those heretofore used, obviates this disadvantage.

As here shown the arbor 10 is of the ordinary tubular form and provided with a pair 40 of disk-like heads 11 at opposite ends, these heads having the usual central apertures 12 to receive the elements on which the arbor is mounted, and eccentric apertures 13 to receive the members whereby the arbor is rotated.

In constructing the arbor according to my invention it is divided transversely into a pair of sections 10' and 10^a, the former of 45 which is comparatively long and the latter 50 of which is relatively short. This latter sec-

tion is provided on its inner end, or that opposite to the one on which the head 11 is fixed, with a diminished extension 14 which is adapted to fit with a frictional hold in the adjacent end of the other section 10'. The 55 extreme end of this extension 14 is preferably curved inwardly as at 15 to facilitate insertion in the section 10', a shoulder 16 being formed at the base of this extension which limits the telescoping movement of 60 the two parts.

The two sections 10' and 10^a are longitudinally slotted as at 17 and 17' along one side thereof, these two slots registering and forming a continuous slot extending between the 65 heads 11 when the arbor is assembled as in Fig. 2. These slots 17, 17' are for the insertion of the ribbon while at the same time they permit of an expansive and contractive movement of the extension 14, and the end 70 of section 10' in which it engages, which insures a firm holding of these parts without undue friction. As will be apparent my improved arbor permits of the ready replacing of the ribbon which can be removed from the 75 long section 10' when the short section 10^a is removed, and replaced by first inserting the new ribbon in the long section 10' and the short section 10^a fitted thereover.

Having thus described my invention what 80 I claim as new and desire to protect by Letters Patent of the United States is as follows:

An arbor for multigraphing machines comprising a tubular element divided at a 85 point between its ends into two sections of unequal length and equal diameter, one of said sections having a diminished tubular extension adapted to fit with a frictional hold in the other section, said tubular extension being curved inwardly at its extremity to facilitate insertion in the said other section and presenting at its base a shoulder limiting insertion thereof into said other section, said sections being provided with longitudinal registering slots extending completely through the meeting ends thereof. 90 95

In testimony whereof I have affixed by signature.

MARION HURLBURT.
